UNITED STATES PATENT OFFICE.

GEORGE E. WARREN, OF BOSTON, MASSACHUSETTS, ASSIGNOR TO CAMPBELL BOSWORTH MACHINERY COMPANY, OF PORTLAND, MAINE, A CORPORATION OF MAINE

SEWING-MACHINE.

1,030,797.

Specification of Letters Patent. Patented June 25, 1912.

Application filed March 16, 1903. Serial No. 147,888.

To all whom it may concern:

Be it known that I, GEORGE E. WARREN, a citizen of the United States, residing at Boston, in the county of Suffolk and State of Massachusetts, have invented certain new and useful Improvements in Sewing-Machines; and I do hereby declare the following to be a full, clear, and exact description of the invention, such as will enable others skilled in the art to which it appertains to make and use the same.

The present invention relates to an improvement in sewing machines and more particularly to sewing machines of the wax 15 thread lock stitch, straight-hook-needle type, of which the commercial harness and leather machines are examples.

The object of the invention is to reorganize and improve sewing machines of the 20 above type and particularly to produce a machine capable of running at high speeds.

Other objects of the invention will be pointed out in connection with various features of the machines hereinafter described.

To the above ends the present invention 25 consists in the devices and combinations of devices hereinafter described and claimed.

In the accompanying drawings illustrating the preferred form of the invention 30 Figure 1^a and Fig. 1^b together constitute a sectional front elevation of the machine; Fig. 2^a and Fig. 2^b together constitute a front end elevation with the cover plate and needle can removed for the sake of 35 clearness; and Fig. 3 is a top plan of the same.

The needle N is a straight hook needle having an enlarged shank. The needle is carried by the needle slide 2 which is received in guideways in the front part of the frame of the machine, guide-plates being provided to support the needle slide in position. The needle shank is received by the needle thimble 3 which consists of a hollow 45 cylindrical pin closed at one end and externally and internally screw threaded at the other end. The needle thimble is received in a circular hole through the needle slide. The portion of the needle thimble 3 which projects beyond the rear side of the needle slide is pierced to receive the shank of the needle N. A set screw 4 is screwed into the thimble and its end bears against the needle shank, holding the latter in place 50 in the thimble. A nut 5 is screwed on to the forwardly projecting end of the needle

thimble and serves when tightened to clamp the needle securely to the needle slide, the rear side of which is vertically grooved to receive and support the needle in operative 60 position. And a spring 6 is secured at its lower end to the needle slide 2 and presses against the inner side of the nut 5. A pin 7 is mounted in the needle slide and projects rearwardly therefrom under the end of the needle shank. This pin serves as an abutment to support the needle against the thrust thereon in its passage through the materials. The needle slide at its lower end is provided with a pin 8 which carries a 70 cam roll which is received in the cam path 9 of the cam disk 10 which is mounted upon the main shaft M of the machine. The cam disk 10 and the cam path 9 therein are illustrated in dash and double dot lines in 75 Fig. 2^b to avoid showing parts behind it dotted.

The above described arrangement is such that, in timed coöperation with the movements of the other parts of the machine, the 80 needle is moved vertically up through the materials, where it receives a loop of thread and then moves vertically down through the materials drawing the loop of thread down with it and delivering it to the shuttle. The 85 peculiar method of supporting the needle in the needle slide secures adequate support therefor to overcome the resistance offered by the work to its passage therethrough by virtue of the pin the end of which is projected under the lower end of the needle shank. At the same time by simply loosening the nut 5 without unfastening the needle in the thimble 3, the needle may be turned to one 90 side to permit the removal and replacement 95 of the bobbin in the shuttle. When the needle is turned to one side it rises out of the groove in the rear side of the needle slide, and when it is turned back again it snaps into the groove under the influence 100 of the spring 6.

The shuttle S is of the discoidal type and receives the bobbin holder 11 within a central aperture formed therein. The bobbin holder delivers its thread through the nose 105 12 which is engaged by the bobbin holder retainer 13 which is secured to the shuttle holder by means of a nut 14. The shuttle S is provided with the point 15 which, after the needle has drawn down a loop of thread, 110 enters the loop and takes it out of the throat of the needle and passes through it, thus

enchaining the needle and shuttle threads. The shuttle S is supported by a shuttle carrier 16, being held in the race-way therein by means of the plate 17. The shuttle carrier is pivotally mounted upon an axis at right angles to the axis of the shuttle and located at substantially the lower edge of the bobbin holder. A depending arm 18 from the shuttle carrier carries upon its end 10 a cam-roll which engages the cam path 19 of the cam disk 20 mounted upon the main shaft M of the machine. The shuttle is rotated continuously in the same direction and at a regular or uniform speed by means 15 of a disk 21 mounted upon the pin 22 secured in a stationary portion of the machine. The disk 21 carries projecting pins 23 which engage recesses in the shuttle formed to receive them. The shuttle is inclined to the vertical and the lower pin 23 engages the corresponding recess in the shuttle, while the upper pin 23 is disengaged from its recess, the pins 23 thus successively engage their corresponding recesses in the shuttle and rotate it positively at all times without interfering with the passage of the loop of the needle thread around it. The disk 21 is formed integral with the pinion 24 which is driven by the 20 gear 25, which is mounted on the main shaft M of the machine and made integral with the cam-disk 20 above referred to. The pinion 24 is one-half the diameter of the gear 25 so that two revolutions are imparted to the shuttle for each reciprocation of the needle, but owing to the fact that the shuttle carrier is oscillated back and forth on its axis once for each reciprocation of the needle the shuttle point is moved into 25 the plane of the needle but once during two rotations, the other rotation being idle, that is to say, lying out of the plane of the needle.

While the illustrated embodiment of the invention employs a shuttle which has one active and one idle rotation it is within the purview of the invention that the shuttle should have one active and two or more idle rotations. The invention is not limited 40 to the use of a shuttle, as a loop taker or other device may be employed for the purpose of enchaining the threads. This shuttle mechanism in and of itself is not claimed herein as it forms the subject matter of a 45 divisional application, Serial No. 247,845 filed Feb. 28, 1905.

The presser foot P is mounted upon the lower end of the presser bar 26 mounted in the bearings 27 and 28 in the front of the head of the machine. The presser bar is normally pressed down by means of the arm 29, the outer end of which engages the head 30 mounted upon the upper end of the presser bar, and the inner end of which is secured to the rock shaft 31 mounted in

the bearing 32 and carrying the arm 33 at the opposite end, said arm 33 having the spring 34 attached at one end to said arm and at the other end to the adjusting device 35 by means of which the tension on the spring may be regulated so as to cause the arm 29 to tend to force the presser bar downward with the desired pressure. A stop-pin 36, adjustably secured by means of the set screw 37 in a hole alongside of the bearing 28 with its upper end in position to engage the under side of the head 30 affords means for limiting the downward movements of the presser bar. Mounted upon the presser bar 26 below the upper bearing 28 is the clamp-sleeve 38, normally held in its lowermost position by the spring 39 which encircles said bar and bears against the lower side of said bearing 28; the clamp sleeve 38 has the clamp lever 40 projected rearwardly therefrom which is adapted to be engaged by the presser bar lifting arm 41 secured to the hollow shaft 42 mounted in the bearing 43 on the rear side of the plate 44, which shaft carries upon its rear end the arm 45 having a cam roll mounted on its end which rests upon the cam surface 46 upon the upper side of the cam-disk 47 mounted on the vertical shaft V of the machine. By this means the presser bar is lifted at the proper time during the operation of the machine in timed coöperation with the feed movement of the awl and the upward motion of the needle, as is usual in this class of machines. The presser foot is also capable of being lifted for the insertion and removal of the work by the arm 48, the outer end of which engages the lower end of the pin 49 secured to the head 30 and projecting down through the bearing 50 located near the bearing 28 above referred to, so that when the arm 48 rises it lifts the presser foot. The arm 48 is mounted upon the front end of the rock-shaft 51 which for convenience passes through the hollow rock-shaft 42 above described and upon the rear end of such rock shaft 51 the arm 52 is mounted which is adapted to be connected to a treadle.

The thread finger F is mounted upon the lower end of a stud 53 which is mounted in a bearing 54 projected downwardly from the overhanging arm, and to the upper end of the said stud 53 is secured by means of set screw the arm 55, to the opposite end of which is pivotally connected the link 56 which in turn is pivotally connected at its rear end to the thread finger lever 57 pivoted at 58 upon a stationary part of the machine and carrying a cam roll which engages a cam path in the upper face of the cam disk 47. By these means the thread finger F is oscillated in timed coöperation with the movements of the other parts of the machine.

The looper L is secured to the lower end of the looper shaft 59 which is mounted in a bearing in the slide 60 mounted in guides on the under side of the overhanging arm. 5 Upon the upper end of the looper shaft 59 is secured the segmental pinion 61 which meshes with the rack 62, carried by the forward end of the slide 63 mounted alongside of the slide 60. The rear ends of the slides 10 60 and 63 carry cam rolls which engage cam path in the lower surface of the cam disk 47. The shape of these cam paths and the above described construction are such that the looper at the proper time during the 15 operation of the machine and after the needle has been thrust up through the materials is caused to partially encircle the needle and lay the thread in the barb thereof. 20 The awl A provided with the enlarged shank 64 is mounted in the lower end of the awl bar 65 carried in a bearing in the slide 66. The vertical motions of the awl are secured as follows:—To the rear side of the 25 awl bar is pivotally attached the link 67 the upper end of which is pivotally attached to the arm 68 which is secured upon the rock shaft 69 mounted in bearings in the frame of the machine, which rock shaft at 30 its rear end carries the arm 70 which is provided with a cam roll which engages the cam path 71 in the cam disk 47. The feed movements of the awl are obtained in the following manner:—Upon the rear side of 35 the slide 66 there is provided a vertical groove which receives a sliding block 72. The other end of the sliding block is received in a groove in the arm 73 which is secured to the front end of the rock shaft 74. 40 The rock shaft carries upon its rear end an arm 75 which is provided with a cam roll which engages a cam groove 76 by means of which oscillations are imparted to the rock shaft 74 which are transmitted through the 45 means described to the slide 66. In order to vary the length of the feed movements the block 72 is supported by a link 77 which is carried by a bell crank lever 78, the upper end of which may be swung back and forth to vary the position of the block 72 in 50 the slots so as to move the block 72 nearer to or farther from the center of the rock shaft 74. The bell crank lever is provided with a detent lever 79 which engages notches 55 in a plate 80 so that said lever 78 may be secured in position to obtain the requisite length of feed. The above described arrangement and the shape of the cams are such that the awl is caused to move downward to penetrate the materials then forward to feed the materials over the position of the needle then upward as the needle advances, then back again to its first position ready to make the next feed movement. 60 The length of the feed movement may be

varied by the means described so as to cause the machine to sew the desired length of stitch.

The take-up, indicated in a general way by the reference letter T, is of the type 70 known as a rotary take-up, and in order to cause it to make its movements in proper cooperation with the other stitch forming instrumentalities it is constructed to make two rotations for each complete movement of the 75 needle. The take-up proper consists of a pin 81 mounted in the end of a lever 82 pivoted at 83 upon a frame 84 which is secured to the pinion 85 revolvably mounted upon the auxiliary shaft. The pinion 85 meshes with 80 a pinion 88 revolvably mounted upon the stud 87 secured in the frame of the machine. The pinion 88 has secured to it the pinion 86 which meshes with the pinion 89 mounted upon the upper end of the auxiliary shaft 85 V. The pinion 89 is splined to the auxiliary shaft and provided with an upwardly extended sleeve which affords a bearing support for the pinion 85 above referred to.

The arrangement thus far described provides for the constant rotation of the take-up pin 81 at a uniform or regular speed, two revolutions for each revolution of the auxiliary shaft V which, being geared by miter gears to the main shaft M of the machine, rotates at the same speed whereas. The lever 82 is supported near the take-up pin 81 by means of a guide 90 so that it may rise and fall in the guide and still be held securely in position. At about the middle 100 of the lever 82 is a stud 91 which carries a cam roll 92 which engages a cam path 93 in the cam disk 94 splined upon the upper end of the auxiliary shaft V. The take-up lever 82 rotates in the same direction as but 105 at twice the speed of the cam disk 94, therefore the take-up lever 82 has imparted to it but one rising and falling movement for each two revolutions.

The take-up mechanism is inclosed by the 110 housing 95 which is recessed or shouldered at the top to receive the part 96 which, for convenience, will be termed the take-up plate. The take-up plate 96 is circular in form and consists of an outer flange 97 115 which is received in the recess in the upper end of the housing 95 and a central portion 98 which is projected forward from the rear part of the plate and which extends toward the marginal portion 97, being separated therefrom by a slot or groove 99 which extends part way around the housing 95 and affords an opening through which the take-up pin 81 may be projected upward. The slot 99 corresponds in position with that 120 portion of the circular path of motion of pin 81 at which the take-up acts on the thread, and the central portion 98 of the take-up plate 96 is supported by the web 125 which connects it with the outer portion 97 130

throughout the remainder of the periphery of the plate. In order to reduce as far as possible the rising and falling movements of the take-up lever 82, the under side of 5 the take-up plate 96 is grooved throughout the portion which is not slotted to afford a space through which the take-up pin 81 may move.

A thread brake, indicated in a general way 10 by the reference character 100, is provided which consists of a plate secured by a screw 101 to the take-up plate, over the opening 102 therein, the screw passing through a slot in the thread brake plate so that the thread 15 brake may be adjusted longitudinally of the thread. By adjusting the thread brake plate back and forth by this means, the amount of take-up can be varied. The thread brake proper consists of a lever 103 pivoted at 104 to the thread brake plate, which lever is provided with a clamping face close to the fulcrum 104 which is adapted to engage the thread and press it against the stud 105 fixed to the thread brake plate. 20 A spring 106 fastened at one end to the rear end of the lever 103 and at the other end to the thread brake plate affords means normally tending to hold the clamping face of the lever 103 against the stud 105. The 25 forward end of the brake lever 103 is provided with a thread eye 107 through which the thread passes.

A cover 108 is provided which rests upon a recess in the upper surface of the annular 30 portion 97 of the take-up plate 96 and provides a shallow space between itself and the central portion 98 of the take-up plate. This cover 108 is removed in threading the 35 machine and replaced when the machine is in operation. It not only serves to keep the parts clean but to keep the thread warm and to limit the space within which it may move.

The operation of the take-up considered 40 by itself is as follows:—The thread entering 45 at the rear of the machine passes between the clamping face of the brake lever 103 and the stud 105 then through the thread eye 107, thence over the top of the take-up plate by the thread truck 109, thence 50 over the thread truck 110, and down through the tube 111 to the looper L. As viewed in Fig. 3, the take-up pin 81 in order to perform its take-up operation rises in the slot 99 at the point 112 and, moving 55 from left to right through the slot 99, engages the thread between the thread truck 109 and the thread eye 107 of the brake lever 103 and carries it out of the straight line joining these two points, thereby causing 60 a strain to be exerted on the brake lever 103 which causes the clamping face thereof to engage and hold the thread against the stud 105. The continued movement of the take-up pin in the slot draws back upon the 65 thread until the take-up pin reaches the po-

sition indicated by the reference character 113 when further movement of the take-up pin in the slot slackens the thread. After the thread is slackened the pin 81 drops out of the loop drawn back by it and disengages 70 itself from the thread. The take-up pin now makes a complete rotation without engagement with the thread when it rises again and the operation above described is repeated.

It is to be noted that since the thread brake 103 is located near the center of revolution of the take-up pin, the movement of the thread between the pin and the brake during the take-up operation is substantially 80 radial so that there is no substantial rendering of the thread about the take-up pin which is a feature of considerable value in a high speed wax thread machine.

The pull-off, indicated in a general way 85 by the reference character O, consists of a lever 114 secured to the rock shaft 115 mounted in a suitable bearing in the housing 95. The rock shaft 115 carries upon its forward end the lever 116 which is provided 90 at its end with a cam roll 117 which engages a cam surface 118 on the lower face of the pinion 89. Since the pinion 89 is splined to the auxiliary shaft V and makes one revolution for each revolution of the 95 main shaft, the pull-off is operated once for each reciprocation of the needle to pull off thread from the supply. The pull-off lever 114 is provided with a thread eye 119 through which the thread passes on its way 100 from the wax pot to the stitch forming mechanism. A spring 120 attached at one end to the pull-off lever 114 and at the other end to a stationary part of the machine serves to return the pull-off lever to its original 105 position after it has performed its pulling off operation. In connection with the pull-off lever a thread brake 121 is employed which consists of a lever 122 pivoted at 123 upon a take-up plate and provided with a 110 clamping face which cooperates with a stud 124 secured to the take-up plate 96 so that it clamps the thread between the clamping face and the stud 124. A spring 125 constantly holds the thread brake lever 122 115 against the thread. The extreme rear end of the brake lever 122 is provided with a thread eye through which the thread passes. The thread after having passed through the thread eye 119 in the pull-off lever passes 120 through the thread eye in the brake lever 122, thence between the clamping face of said lever and the stud 124 against which it clamps the thread at each time that the pull-off lever starts to make its pull-off movement. This prevents the pull-off lever from acting as a take-up.

A wax pot W is provided through which the thread passes on its way to the machine. The arrangement of the wax pot and the 125

pull-off lever is such that the thread, after passing from the stripper 126, passes onward in a straight line to the thread eye 119 of the pull-off lever 114 and thence back to 5 the thread eye of the thread brake lever 122, so that the first movement of the pull-off lever in the direction to pull off thread from the wax pot operates to clamp the thread by means of the thread brake 121 and then to 10 pull thread from the wax pot W.

Suitable means for heating the various parts of the machine are provided. The steam pipe 127 leads to the steam jacket 128 which is mounted upon the rear of the take-up plate 96. From this jacket 128 the steam passes through the pipe 129 to the steam jacket 130 for the wax pot, thence through 15 the pipe 131 to the steam chamber in the overhanging arm for heating the thread 20 on its way to the stitch forming instrumentalities and for heating the looper and thread finger. Thence it passes through the pipe 132 to the steam jacket 133 which by conduction and radiation heats the shuttle, 25 and thence it is discharged.

The main shaft M of the machine is journaled in suitable bearings 135 and 136 in the base of the machine, and the forward end of the main shaft is provided with an auxiliary bearing 137 which is carried by the 30 front plate 138 of the machine. Upon the rear end of the main shaft M is secured the usual grooved pulley wheel 139 from which the machine may be driven from any convenient 35 source of power.

The auxiliary shaft V is mounted in vertical bearings 140 in the base and 142 in the overhanging arm of the machine and is geared to the main shaft M by miter gears 40 143 and 144 so that the main shaft M and the auxiliary vertical shaft V rotate at the same speed. The base of the machine 145 is a box-shaped structure which is provided upon its upper rear end with a surface 146 45 to which the base 147 of the overhanging arm 148 is bolted.

The bobbin holder 11 is removed from the shuttle by removing the cover plate 149 pivoted upon the upper edge of the front plate 50 138 and the throat plate 150, turning the machine so that the shuttle is in its rear position. The nut 5 by which the needle is secured in position is loosened and the needle is thrown to one side out of its slot in the 55 rear side of the needle slide, the cam disk 10 being provided with holes through which the nuts 5 and 14 may be reached. Then the nut 14 of the bobbin holder retainer 13 is released and the retainer is turned to one 60 side. The bobbin holder may then be removed and provided with a full bobbin and again be replaced in the machine. The front plate 138 is provided with openings through which wrenches may be inserted to 65 turn the nuts 5 and 14.

The operation of the machine of the drawings is as follows: Assuming the parts to be in the position shown in the drawings, with the shuttle hook just entering the loop of thread drawn down by the needle, the 70 needle at the bottom of its loop-drawing stroke, the awl at the top of its stroke, and the take-up down, that is to say, running idle, the shuttle hook first enters the loop and the shuttle passes therethrough, the 75 pull-off giving up thread to the shuttle, and just before the shuttle completes its movement through the loop the take-up is lifted into position ready to engage the thread between the thread brake 100 and the thread truck 109, and after the shuttle has passed through the loop the take-up engages the 80 thread and sets the thread brake 100 and pulls back the loop of thread which has been passed around the shuttle and pull the 85 shuttle thread into the materials. After the take-up has completed its taking-up movement it slacks up upon the thread which it has engaged and then drops out of engagement therewith and runs idle until the formation of the next stitch. After the completion of the taking up operation the presser foot is lifted, and the awl, having previously made its downward movement penetrating the materials, now begins its 90 feed movement and feeds the work. After the feed movement is completed the presser foot again drops upon the materials and holds the same during the upward movement of the awl and the needle. The 100 upward movement of the awl does not begin until after the presser foot has dropped upon the materials although the upward movement of the needle has begun previous to this time because the needle has to rise 105 some distance before it reaches the materials. The awl and needle proceed upward together, the awl retreating slightly in advance of the needle. The looper, having moved away from its position over the 110 needle, now moves toward and around the needle and loops the thread in the barb thereof. With the completion of the upward movement of the needle the looping movement is completed and the needle begins its retracting movement, the awl during this time feeding back to its original position. The needle now descends, and the 115 thread finger, which during the feeding movement of the awl had engaged and formed a bight in the thread between the looper and the work, now gives up thread to the retracting needle. Before the needle has completed its downward movement the shuttle begins to move forward toward the 120 path of motion of the needle and at the time the downward movement of the needle is completed the shuttle hook enters the loop of thread pulled down by the needle and the operations above described are re- 130.

peated. The pull-off movement of the pull-off begins shortly after the beginning of the operative movement of the take-up and is completed slightly before the completion of 5 such movement, and the pull-off then stands still, holding the thread taut until after the 10 needle has begun its downward movement, when it begins to retract to slacken the thread. By causing the shuttle to make two 15 or more revolutions for each reciprocation of the needle, the time required for the shuttle to pass through the loop of thread pulled down by the needle is reduced in amount, and by causing the take-up to operate in the 20 manner described the proportionate part of the complete cycle of movement which is occupied by the take-up operation is much decreased without interfering with the operations of the other parts of the machine. It 25 is desirable in this class of machines that the taking up of thread should begin rapidly and should be completed slowly, and by the means described the take-up pin 81 when it first engages the thread draws back upon 30 the same rapidly, but as the pin approaches the position 113 the amount of thread drawn by the take-up in proportion to the distance through which the take-up moves is gradually diminished, whereby the thread is 35 pulled into the materials and against the stress incident thereto with a gradually decreasing speed until at last the take-up operation is completed when, although the speed of motion of the take-up is undiminished, it 40 draws no more thread, and during an appreciable length of time the thread is held in the position to which it has been drawn by the take-up and it is given time to set in the position which it has assumed in the 45 materials before the take-up again slackens its stress upon the thread. Then the take-up, after slackening the thread, drops out of the bight formed thereby and permits the looper and thread finger to form a bight in the thread preparatory to looping the needle when it again rises through the materials.

It is to be noted that since the shuttle is a rotary shuttle as distinguished from an oscillating or reciprocating shuttle, it is not 50 required to change its direction of motion during each complete cycle of operations of the machine but persistently rotates in the same direction and at a constant speed. Furthermore it is to be noted that the take-up, as distinguished from oscillating or reciprocating take-ups, moves always in the same direction and at the same speed and that it is caused to engage the thread only at such time during the operation of the 55 machine as it is desired that the thread should be taken back from the shuttle around which it has been passed. It is a matter of considerable importance in the production of high speed sewing machines that parts 60 which have the greatest movement should

not be reciprocatory or oscillatory, and it is believed that the present invention is the first machine having a shuttle and take-up which rotate a plurality of times for each cycle of operations of the parts of the machine. 70

The present invention is not limited to the specific embodiment thereof illustrated in the drawings but may be embodied in other forms. 75

The features of the present invention are not limited to embodiment in straight needle sewing machines as they are susceptible of embodiment in sewing machines employing a curved hook needle, but it is believed that 80 they are the more valuable in straight needle machines for reasons apparent to those skilled in this art.

Having thus described the invention what is claimed is:— 85

1. A sewing machine, having, in combination, a reciprocating hook-needle and means for actuating it, a rotary shuttle on the same side of the work as the needle, a rotary take-up and means for actuating the shuttle and 90 take-up to make a plurality of rotations in the same direction to each reciprocation of the needle, and to engage the thread once during each reciprocation of the needle, substantially as described. 95

2. A sewing machine, having, in combination, a reciprocating hook-needle and means for actuating it, a rotary shuttle on the same side of the work as the needle, a rotary take-up, and means for imparting a regular or 100 uniform rotary motion to said shuttle and take-up to cause the shuttle and take-up to make a plurality of rotations in the same direction to each reciprocation of the needle and to engage the thread once during each 105 reciprocation of the needle, substantially as described.

3. A sewing machine, having, in combination, a needle, a shuttle, a rotary take-up, and means for causing the take-up to engage 110 the thread to pull upon the same to take up the thread of the loop through which the shuttle has passed, then to slacken up upon the thread and then to disengage itself therefrom, substantially as described. 115

4. A sewing machine, having in combination, a needle, a shuttle, a rotary take-up, a take-up plate across which the needle thread runs from the supply to the needle, said take-up plate being provided with a 120 slot, a take-up pin, means for moving the take-up pin through the slot and for raising it up and down in the slot so that it shall engage the thread when raised and take up thread, substantially as described. 125

5. A sewing machine, having, in combination, a needle, a shuttle, a take-up plate over which the thread leads to the needle, said plate being provided with a segmental circular slot, a take-up pin, means for rotating 130

the pin under the slot, and means for projecting the pin up through the slot to engage the thread upon alternate rotation of the take-up, substantially as described.

5. 6. A sewing machine, having, in combination, a needle, a shuttle, a take-up, including a revolving thread engaging device, and a thread guide fixed during the taking up operation and located approximately at the center of motion of said device so that the thread does not render around said device during the take-up operation, substantially as described.

7. A sewing machine, having, in combination, a needle, a shuttle, a take-up having a revolving thread engaging device, and two fixed thread guides located respectively outside of, and substantially at the center of, the path of motion of said device, substantially as described.

8. A sewing machine, having, in combination, a straight hook-needle, a shuttle located on the same side of the work as the needle, a take-up rotating twice for each reciprocation of the needle and located on the opposite side of the work from the needle in proximity to the lead of the thread, a thread brake on the remote side of the take-up, a pull-off, a thread brake on the proximate side of the pull-off, and means for actuating the parts to cause the pull-off to pull off the thread from the supply and deliver it to the needle and shuttle, the take-up acting during alternate rotations to engage the thread and take up the loop of thread through which the shuttle has passed, substantially as described.

9. A lock stitch leather sewing machine, having, in combination, a horizontal base and an overhanging arm, a main shaft in the base, a needle supported by a needle slide in guides in the base, a cam on the main shaft for actuating the needle to impart thereto one reciprocation for each rotation of the main shaft, a shuttle located in the base in proximity to the needle, a shuttle carrier, means for rotating the shuttle twice for each reciprocation of the needle, means for moving the shuttle toward and from the needle once for each reciprocation of the needle, an auxiliary vertical shaft in the overhanging arm driven from and at the same speed as the main shaft, a rotary take-up pivotally mounted on a frame on the auxiliary shaft, gearing for rotating the take-up twice for each rotation of the main shaft, and a cam on the main shaft for raising and lowering the take-up into position to engage the thread once for each rotation of the main shaft, substantially as described.

10. A sewing machine, having, in combination, a base, a horizontal main shaft mounted in bearings in the base, a vertical

auxiliary shaft mounted in bearings in the base, an overhanging arm, a reciprocating hook-needle located in the base and actuated from the main shaft, a rotary shuttle located in the base and actuated from the main shaft, a rotary take-up loosely mounted upon the upper end of the auxiliary shaft, a pull-off, a thread finger, a looper, an awl, and a presser foot, and means for actuating the take-up, pull-off, thread finger, looper, awl, and presser-foot from the auxiliary shaft, substantially as described.

11. A lock stitch leather sewing machine, having, in combination, a base, a horizontal main shaft supported therein, a reciprocating needle, means for actuating the needle from the main shaft, a rotary shuttle, means for rotating the shuttle from the main shaft a plurality of times for each rotation of said main shaft, means for supporting the shuttle and moving it toward and from the needle once during each rotation of the main shaft, a vertical auxiliary shaft driven from and at the same speed as the main shaft and supported in bearings in the overhanging arm, a rotary take-up, an awl, a presser foot, a looper, and a thread finger supported from the overhanging arm, and a cam disk on the auxiliary shaft provided with cam paths or surfaces for actuating the take-up, awl, presser foot, looper and thread finger, the take-up being mounted upon the auxiliary shaft but not secured thereto and being actuated so that it shall engage the thread once for each reciprocation of the needle, substantially as described.

12. A sewing machine, having, in combination, a hook-needle, a rotating shuttle, a rotating take-up, said shuttle and take-up being arranged to act on the thread once during each reciprocation of the needle, a looper, means for actuating the needle and looper and means for imparting a plurality of rotations to the shuttle and take-up for each reciprocation of the needle, substantially as described.

13. A sewing machine, having, in combination, a hook-needle, a rotary shuttle, a rotary take-up, said shuttle and take-up being arranged to act on the thread once during each reciprocation of the needle, a thread finger, a looper, means for actuating the hook needle, thread finger and looper, and means for imparting a plurality of rotations to the shuttle and take-up for each reciprocation of the needle, substantially as described.

In testimony whereof I affix my signature, in presence of two witnesses.

GEORGE E. WARREN.

Witnesses:

HORACE VAN EVEREN,
FARNUM F. DORSEY.
